UNITED STATES PATENT OFFICE.

EMANUEL N. GALANIS, OF NEW YORK, N. Y.

MINER'S SAFETY CAP.

Application filed February 27, 1922. Serial No. 539,420.

To all whom it may concern:

Be it known that I, EMANUEL N. GALANIS, a citizen of the United States, residing at the city and county of New York and 5 State of New York, have invented certain new and useful Improvements in Miners' Safety Caps; and I do declare the following to be a full, clear, and exact description of the invention, such as will enable others 10 skilled in the art to which it appertains to make and use the same, reference being had to the accompanying drawings, and to the characters of reference marked thereon, which form a part of this specification.

15 This invention relates to caps and has special reference to caps for use by miners.

It is well known that the miner who works underground is exposed to several dangers which are peculiar to that class of 20 work, among which is that of falling rocks which may strike his head as they drop from the ceiling to the floor, and that of the electrical conductors which are strung throughout the mine and are often so low that the 25 miner will strike them with his head and receive severe electrical shocks which may even result in his death.

It is the object of this invention to provide a cap for use by underground workers, 20 which shall be provided with means that will serve to protect the wearer from injury due to falling rock of moderate size, and from electric shock due to accidental contact with the insulated electrical conductors.

35 It is also a further object of this invention to produce a cap that is provided with means whereby it may be adjusted to fit the head of the wearer, so that it will not be necessary to manufacture more than one size.

40 In order to more clearly describe my invention, I shall have reference to the accompanying drawing in which—

Fig. 1 shows a side elevation of my improved safety cap;

45 Fig. 2 is a vertical section taken on line 2—2, Fig. 1;

Fig. 3 is a view showing the cap in place on the wearer's head, and the face protectors in inoperative position;

50 Fig. 4 is a view similar to Fig. 3, showing the face protectors in operative position;

Fig. 5 is a rear view of my cap showing it in place on the wearer's head;

55 Fig. 6 is a section showing a modified form of construction; and

Fig. 7 shows a section of another modified form of construction.

The same reference numerals will be used to indicate the same parts throughout the several views.

My improved cap consists of a crown piece which is made up of an outer layer 1 of hard material such as fiber, leather or any other similar material which will resist shocks and blows due to the impact of a hard body. 65 On the inside of layer 1 is a second layer of elastic cushioning material 2 such as felt, and inside of this is a third layer 3 of waterproof electrical insulating material. Secured to the inner surface of the crown piece 70 are spaced vertical stays 4, which may be made of rubber, fiber, leather or any similar material, which serve to space the inside of the cap from the wearer's head, whereby air is permitted to pass into the cap and out 75 through the ventilator openings 5 of which several are provided along the upper edge of the sides of the cap and in the top thereof. If it is desired to add to the rigidity of the top 6 of the cap, strips 7 of fiber may 80 be secured to the inside thereof. My cap is provided with the usual vizor 8 and metal lamp support 9 in the upper end of which I provide two holes 10. To the back of the cap I provide a triangular portion 11 of 85 flexible electrically non-conducting material whose function it is to project downwardly over the neck so as to protect it from contact with electrical conductors. In order to provide protection for the face and ears, I 90 provide on each side of the cap a flap 12 which may be brought around the sides and front of the face in the manner shown in Figs. 1, 2 and 4, or secured in the inoperative position shown in Figs. 3 and 5. Snap fasteners 13 are provided in the ends of members 12 in the manner shown. If it is desired to provide ventilation for the face, the members 12 may be provided with a plurality of parallel slots 14.

When the miner enters the mine and passes through parts thereof where there are a number of electrical conductors, he secures the members 12 about his face in the manner shown in Fig. 4; his head will then be effectively guarded against injury due to electrical shock, and also from falling coal or rock. The triangular member 11 extending over the neck protects the latter.

In Fig. 6 I have shown a modification in 110

which I provide two members 15 of hard material such as fiber or leather, between which I place resilient means such as springs 16. Next to the innermost member 15 I provide a layer of elastic material 17 and this is covered on the inside with an insulating waterproof fabric 18. It is evident that a cap constructed in accordance with Fig. 6 will afford a great amount of protection 10 against injury due to falling rocks, and will also be an effective electrical insulator. Where a simple and cheap construction is desired, I may make the body of the cap of a layer of hard fibrous material 19 (Fig. 7) 15 and line the inside thereof with an insulating fabric lining 20. I may also make my cap in the manner shown in which automobile tires are formed, that is, by building up the body thereof from rubberized fabric, 20 which can subsequently be cured in a vulcanizer. Such a construction will be electrically non-conductive and can be made of sufficient thickness and rigidity to render it 25 of great protective value against injury from falling rocks.

I am aware that the objects of my invention can be attained by structures specifically different from those described by me, but I consider that I am the inventor of the

broad idea of a cap that combines protection 30 against electrical injury as well as against blows.

Having now described my invention, what I claim is—

1. A miner's safety cap composed of an 35 outer layer of hard material, an intermediate layer of yielding material, an inner layer of non-absorptive electrical insulating material, and electrical insulating means connected to the rear of the cap and extending 40 downwardly over the wearer's neck to protect the same against injury from contact with live electrical conductors.

2. A miner's safety cap composed of an 45 outer layer of hard material, an intermediate layer of yielding material, an inner layer of non-absorptive electrical insulating material, electrical insulating means connected to the rear of the cap and extending downwardly over the wearer's neck to protect the 50 same against injury from contact with live electrical conductors, and electrical insulating means adapted when in operative position to protect the wearer's face from injury due to contact with electrical conductors. 55

In testimony whereof I affix my signature.

EMANUEL N. GALANIS.
